UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

STEAM-TURBINE.

1,098,316.

Specification of Letters Patent. Patented May 26, 1914.

Application filed June 12, 1912. Serial No. 703,123.

To all whom it may concern:

Be it known that I, CHARLES W. DAKE, a citizen of the United States, residing at Chicago, in the county of Cook and State 5 of Illinois, have invented a certain new and useful Improvement in Steam-Turbines, of which the following is a specification.

My invention relates to steam turbines and is illustrated somewhat diagrammatically in 10 the accompanying drawings, wherein—

Figure 1 is a detail section through a portion of the turbine; Fig. 2 is a detail section through a portion of the turbine; Fig. 3 is an enlarged detail view of a portion of what 15 is illustrated in Fig. 1; Fig. 4 is a side elevation of a ring which forms one side of each of the buckets and one side of one of the steam passageways; Fig. 5 is a side elevation of the ring which separates the two friction 20 passages.

Like parts are indicated by the same numerals in all the figures.

1 is one side of the casing, only a portion of it being shown. 2 is the other side of 25 the casing, only a portion of it being shown. 3 is the steam inlet, 4 the exhaust outlet, 5 the steam passageway which leads to the nozzle 6, and 7 is the spider of the rotor mounted on the shaft 11 and secured in position by the nut 12.

30 8, 8 are the buckets of a steam turbine and 9 and 10 the rings which form the sides of the bucket and the sides of the two annular slots through which the steam passes. 35 12, 12 are the bolts whereby the ring 9 is held on and against the edges of the buckets to complete them. 13, 13 are the other sides of the buckets and the means whereby the buckets are attached to the rotor. These 40 parts are not here more specifically described because they are the subject matter of another application.

The drawings illustrate a practical form 45 of apparatus, but I have not shown a complete structure and the showing is in a sense fragmentary and diagrammatic, but it is sufficient to illustrate the invention.

The use and operation of my invention are 50 as follows: Assuming the structure made as illustrated in Fig. 1 and completed so as to have a finished casing with the buckets and annular slots all the way around, the steam, and by this term it will be understood that I mean to include any driving fluid, is introduced through the passageways and the noz-

zle 6. This nozzle discharges on both sides of the sharpened ring 10 into the two annular slots and is set so that its current of steam is directed at an inclination to the tangent of the rotor. As the steam passes forwardly and outwardly through the annular slots thus formed in the rotor, it tends to set the rotor in motion by the friction of the steam upon the walls of the slots. The exit of the steam from these slots is retarded by 60 the presence of the buckets 8, 8 which act as deflectors of successive sections or portions of the stream of steam. By properly proportioning the cross sectional area of the buckets with reference to the cross sectional area of 65 the steam nozzle 6, the steam can be caused to pass out of the annular slots 10 at all points around their peripheries so that all the buckets are receiving some of the steam and each is contributing something to the forward 70 motion of the rotor. The steam finally escapes from the buckets into the casing, whence it is led or discharged in any desired manner. Thus in my steam turbine I 75 combine the frictional action of the steam with the action due to its deflection to react upon the steam so as to increase its frictional action.

By the term bucket, or reversing bucket as I am using it, I wish it to be understood 80 as including all those forms of buckets wherein and whereby the current is reversed or where the current comes into the bucket from one direction and leaves it in a reverse direction. The point is that the bucket 85 should be such that the current which is discharged into it in the general direction of rotation of the bucket leaves it in a reverse direction so that the bucket is advanced by the reaction of the reversed current. The 90 arrangement of the slot with reference to the buckets is such that the current of fluid is discharged into both in the general direction of their forward motion and escapes from the discharge of the bucket in the opposite direction. Thus the rotor is advanced by the friction of the current of material in 95 the slot and by its impact on the bucket. I have shown the buckets as on the periphery of the rotor, the slots as associated therewith 100 and the nozzle or means for supplying the current as interior to the whole, but obviously the three parts can be arranged in any desired manner to bring about the result sought for.

I claim:

1. A turbine comprising a casing and a rotor having an annular slot thereabout and reversing buckets into which the slot opens and means for discharging a current of fluid into the slot and buckets in the general direction of their rotation.
2. A turbine comprising a casing, a rotor having an annular slot thereabout and reversing buckets exterior but opening into the slot and means interior to the slot for discharging a current of fluid into the slot and buckets in the general direction of their rotation.
3. A turbine comprising a casing and a rotor, the rotor having an annular slot and a series of buckets beyond the slot and opening thereinto and each having a reversing passage and means for discharging a current of fluid into the slot and buckets.
4. A turbine comprising a casing and a rotor having a series of annular slots and a series of peripherally arranged buckets, the slots opening into the buckets, and a nozzle for supplying the driving fluid to the slots.
5. A turbine comprising a casing and a rotor having a series of annular slots and a series of peripherally arranged buckets, the slots opening into the buckets, and a nozzle for supplying the driving fluid to the slots, 30 the cross sectional area of the buckets and nozzle being such as to increase the pressure of the same in the slots before it escapes into the buckets.
6. A turbine comprising a casing, a rotor, 35 a series of buckets on the rotor, a ring to form the outer edges of the buckets but inwardly projecting beyond the buckets, a second ring secured to the edges of the buckets between the rotor wall and the first 40 ring so as to form two annular slots and a nozzle adapted to discharge steam from within the annular slots thereinto.

Signed at Chicago, Illinois, this 10th day of June, 1912.

CHARLES W. DAKE.
